UNITED STATES PATENT OFFICE.

HUGO LENTZ, OF HALENSEE, NEAR BERLIN, GERMANY.

VALVE-GEAR.

No. 852,389.

Specification of Letters Patent.

Patented April 30, 1907.

Original application filed December 22, 1905, Serial No. 292,964. Divided and this application filed December 6, 1906.
Serial No. 348,574.

To all whom it may concern:

Be it known that I, HUGO LENTZ, a subject of the German Empire, and a resident of 123 Kurfürstendamm, Halensee, near Berlin, in the Empire of Germany, engineer, have invented certain new and useful Improvements in and Relating to Valve-Gears, of which the following is a specification.

This invention relates to means for diminishing the counter-pressure in explosive gas engines when starting, and the object of the invention is to provide effective means for obtaining an additional opening of the exhaust valve during the period of compression when starting the motor. According to this invention, said means for diminishing the counter-pressure consist in a movable boss arranged in the reciprocating distributer containing the exhaust valve, which boss rocks with the distributer, being pressed toward the interior of the distributer by a spring and caused to project by the displacement of an axial wedge or an equivalent part, in order to act upon the exhaust member.

25 In the accompanying drawing: Figure 1 is a view showing the means for operating the exhaust valve. Fig. 2 shows a detail, and Fig. 3 is a diagram of the distribution.

It is known that explosion engines usually operate with exceedingly high degrees of compression and for this reason various means have been heretofore provided in these engines which on starting permit of opening the exhaust during the compression period, for the purpose of reducing the counter-pressure to about atmospheric pressure, thereby rendering it possible to start with a small absorption of power. The present invention comprises a means of this kind applicable to valve distributions with reciprocating distributer. This means consists of a movable boss sliding in the rocking distributing cam or plate and pressed back in such a manner that it is effaced or lodged within the distributing member during normal running; in starting, this boss, being lifted by appropriate means, projects in such a manner as to open the exhaust valve during a portion of the compression period, thereby preventing the establishment of a high counter-pressure in the cylinder.

In Fig. 1, *a* designates the exhaust cam of an engine operated with a cycle of four phases, in which the distributing shaft rotates at one

half the speed of the driving shaft; this cam is provided with a fixed boss *b*, for the regular opening of the exhaust valve, and in a recess an auxiliary boss *c* pressed inward by a spring *d*. By way of example of the operation of this boss, Figs. 1 and 2 indicate a movable key *e* sliding in a bore in the rocking shaft of the distributer. The displacement of the key toward the right hand (Fig. 2) serves to lift the auxiliary boss *c* and to open the exhaust member.

In the diagram forming part of Fig. 1, the arc 3—4 represents the normal aperture of the valve, during the exhaust period; in the diagram Fig. 3, the arcs 1—2, 2—3, 3—4, 4—1, represent respectively the compression, ignition and explosion, exhaust and suction periods of a cycle. In this latter, the fixed boss *b* of the cam or distributer opens the valve while the crank describes the arc 3—4. If the auxiliary boss *c* be lifted and caused to project, the exhaust member is again opened during the compression period 1—2 and this during the whole of the time occupied by the crank in describing the angle *g*—*h*, so that in starting any increase of pressure during the compression period, capable of increasing the resistances, may be obviated in a simple and effective manner.

The key or wedge which in this particular arrangement serves to effect the displacement of the auxiliary boss, may be replaced by any other part capable of fulfilling the same functions. Thus, in place of a key or wedge, wheel transmission gear may be employed, for example, by giving to the auxiliary boss the form of a rack in engagement with a wheel arranged in the recessed shaft of the distributer.

The mechanism described by way of example, for the displacement of the auxiliary boss permits of grouping the whole of the parts in a very restricted space and also of dispensing with certain parts.

Having now particularly described and ascertained the nature of my invention and in what manner it may be performed, I declare that what I claim is:

1. In an explosion motor, means for diminishing the counter-pressure in starting, which consist in a movable boss arranged in the reciprocating distributer controlling the exhaust valve, which boss rocks with the distributer and being pressed toward the inter-

rior of the distributor by a spring and caused to project by the displacement of an axial wedge or an equivalent part, in order to act upon the exhaust member substantially as described.

2. In an explosion motor, means for diminishing the counter-pressure in starting, which consist in a movable rocking boss arranged in the reciprocating distributor, said boss being connected with a part serving to displace it, for example a rod capable of axial displacement in such a manner that when this part is acted upon this movable boss is either caused to project or to recede substantially as described.

3. In a gas engine, the combination of an exhaust valve, a rocker adapted to operate the same, a pin carried by the rocker and movable in and out of active position, the pin being adapted to open the exhaust valve 20 during the compression period, and means for operating the pin.

In testimony whereof I have hereunto placed my hand, at Berlin, Germany, this 15th day of Novbr 1906.

HUGO LENTZ.

In the presence of two witnesses—

WOLDEMAR HAUPT,
HENRY HASPER.
